UNITED STATES PATENT OFFICE.

DANIEL HERBERT NOBLE, OF SHERIDAN, MONTANA.

RAIL-JOINT.

SPECIFICATION forming part of Letters Patent No. 707,447, dated August 19, 1902.

Application filed October 18, 1901. Serial No. 79,099. (No model.)

To all whom it may concern:

Be it known that I, DANIEL HERBERT NOBLE, a citizen of the United States, residing at Sheridan, in the county of Madison and State of Montana, have invented certain new and useful Improvements in Rail-Joints; and I do hereby declare the following to be a full, clear, and exact description of the invention, such as will enable others skilled in the art to which it appertains to make and use the same.

My invention relates to rail-joints; and it consists of certain novel features of construction, as will be hereinafter clearly set forth, and illustrated in the accompanying drawings, made a part of this application.

The object of my invention is to provide means for uniting the ends of rails employed in forming a railway-track, and while I shall describe the preferred construction deemed most desirable it will be understood that I wish to comprehend such substantial equivalents and modifications as may be considered to fall fairly within the scope of my invention.

In the accompanying drawings, Figure 1 is a top plan view of two ends of a rail fitted in a special manner to coöperate with each other, whereby the strength of the union thus formed will be all that can be desired. Fig. 2 is a perspective view of one of the rails so shaped as to form the style of joint or union illustrated in Fig. 1. Fig. 3 is a top view of the end of the rail shown in Fig. 2.

In order to conveniently refer to the several features of my invention and their coöperating accessories, numerals will be employed, of which 1 and 2 illustrate the ends of two separate rails of a railway-track, while the line of juncture extending from the numeral 3 to the numeral 4 illustrates the preferred form of shaping the ends of the rails so as to provide the form of union illustrated.

By reference to Figs. 1 and 2 it will be observed that a vertical cut is made upon the meeting ends of the two rails, so as to provide the surfaces indicated by the numerals 5, 6, 7, and 8 and the laterally-extending surfaces 9, said parts being the same on both rails, and it is therefore obvious that when the two rails thus shaped are brought together they will interlock or coöperate with each other to provide the line of union indicated by the nu-

merals 3 and 4. By thus constructing the ends of the two rails it will be observed that the longitudinal expansion and contraction of the rails will be in no wise interfered with or limited. When the rails thus shaped are joined together, they are permanently secured in such coöperating position by means of the usual fish-plates, one upon each side of the web 11, the plates being locked in position by passing the retaining-bolts 12 through suitable apertures 13, as illustrated in Fig. 2.

The surface indicated by the numeral 5 being the same upon both rails, it is obvious that when the rails contract said surfaces will move away from each other, leaving a slight crack or opening which will again be closed upon the extension of the rails, the contacting surfaces 6 upon the two rails merely moving or rubbing against each other during the operation of contraction and expansion.

If deemed desirable, the apertures 13 in the web of the rail may be made slightly elliptical to compensate for any expansion of the rails, and thus taking a severe strain of such expansion off of the bolts 12, as will be incident to the use of my improved rail-joint, it being understood that any preferred number of bolts 12 may be employed or that any preferred variety of fish-plate may be used. The ends of the rails may be very quickly and expeditiously shaped in the manner above described by suitable tools or appliances, thus reducing the work of uniting the ends of two rails together to a minimum.

While I have described and herein illustrated the preferred construction which may be adopted in providing a suitable locking-joint for rails, it will be understood that I desire to comprehend in this application all such substantial equivalents and modifications as may be considered to fall fairly within the scope of my invention.

Having thus fully described the construction and manner of applying my invention to use, further reference to the details is unnecessary.

What I claim as new, and desire to secure by Letters Patent, is—

A rail-joint consisting in so shaping the meeting ends of each rail that each end will be provided with an obliquely-disposed surface 5 in its central or rib portion, each rail

also having the longitudinally-disposed surfaces 6, 7 and 8 paralleling each other, each rail being further provided with the transversely-disposed surfaces 9, said parts on each rail being parallel with the parts on the other rail all substantially as specified and for the purpose set forth.

In testimony whereof I affix my signature in presence of two witnesses.

DANIEL HERBERT NOBLE.
